Henry M. Rose

ATTORNEY

UNITED STATES PATENT OFFICE.

EDWIN J. NELSON, OF UTICA, NEW YORK.

WASHING-MACHINE.

1,090,406.

Specification of Letters Patent. Patented Mar. 17, 1914.

Application filed February 1, 1912. Serial No. 674,684.

To all whom it may concern:

Be it known that I, EDWIN J. NELSON, a citizen of the United States, residing at Utica, in the county of Oneida and State 5 of New York, have invented certain new and useful Improvements in Washing-Machines, of which the following is a specification, reference being had therein to the accompanying drawing.

10 My invention relates to an improved washing machine, and I declare that the following is a full, clear, concise and exact description thereof, sufficient to enable one skilled in the art to make and use the same, 15 reference being had to the accompanying drawings, in which like reference characters refer to like parts throughout.

The apparatus is shown as a dish-washing machine, but I do not restrict myself by 20 such term.

The device is an apparatus which can be conveniently used by the housewife, being of compact form and having means operative, preferably by electrical power, to 25 effect the cleaning and drying of various articles.

In the drawings Figure 1 is a side view of the device in section, and Fig. 2 is a detail view in section of a portion of the 30 device. Fig. 3 is a detail.

Referring to the figures in detail, A represents an ordinary house sink and B a washing and drying tank, which in this instance is shown as cast integral with the 35 sink A, but not necessarily so. I do not limit myself in this particular, however, as means can be readily applied by any mechanic for the mounting of the tank B on the sink A, either fixedly or removably.

40 Hot and cold water faucets are shown above the sink and the tank at 1, 2, 3 and 4. The sink A has a discharge pipe A'. The tank B has discharge pipe B' and an overflow at B''. The discharge pipe from the tank is 45 provided with a stop-cock C placed between the bottom of the tank and the point where the overflow discharges into the waste-pipe B'. A wire crate is shown by D, one portion, D', being vertical and secured, as at d, 50 to the wall of the tank. The portion D receives the dishes or articles to be cleaned, shown at x, and holds them from resting on the bottom and less likely to be broken when put in the tank. The portion D' keeps the 55 dishes from the cleaning mechanism, which

will be described. A wire-net cover D'' is laid over the dishes and holds them in place.

The casting, indicated in general at E, is bolted, as at e, to the tank. It may be integral with its tank. The part E comprises a chamber in something like cup-form so mounted as to open into the tank B. It has a lateral projection or arm E' on which is mounted proper motive power F, such as an electric motor, to which, it will be understood, electric current is carried by suitable wires and connections. The shaft G of the motor is connected by suitable chuck G' to shaft H, which is carried in suitable 60 housings in the casting E. At the inner end of the shaft is mounted a revolving agitator J with blades j and which, being rotated by the revolution of the shaft, sets up currents throughout the body of water which is put in the tank for the washing of 65 the dishes or other articles.

K represents a stud, screw-mounted in the casting E, and projecting into the interior of casting E. The inner end of the stud K carries a head L with a shifter-finger l 80 formed to engage with the sleeve M which is loosely mounted on the shaft H, but is adapted by manipulation of the stud K to engage with the sleeve J' on which the blades j of the agitator are mounted. A 85 gasket k' is provided to seal the ports k'', in the casting E, when the stud K is in the position shown in Fig. 1.

The operation of the motor rotates the shaft H and the agitator J. This is carried 90 on until the contents of the tank are thoroughly cleaned, after which the water may be run off and clean water let in to rinse the articles by further rotation of the agitator. After the articles are thoroughly 95 cleaned the water is again let out. Manipulation of the stud K brings sleeve M into engagement with sleeve J' and also opens the ports shown at K''. R is a fan mounted on sleeve M and the rotation of sleeve M, 100 as just noted, creates currents of air throughout the chamber and tank, increased by the rotation also of the fans of the agitator J. When the sleeve M is out of engagement with sleeve J' the fan R will be substantially at rest.

Having described my invention, what I claim as new, and desire to secure by Letters Patent, is:

1. In an apparatus of the character de- 110

scribed, the combination of a tank, a chamber opening into the tank, rotating paddles mounted in said chamber and means for operating one set of said paddles alone or both in unison.

2. An apparatus of the character described comprising a tank, means for agitating the contents of the tank, a fan for directing air currents upon the said contents and means whereby to connect and disconnect the said agitating means and the said fan.

3. An apparatus of the character described comprising a tank, a chamber opening into the tank and having ports therein, an agitator in the chamber, a fan mounted

in the chamber and means connecting the fan with the agitator and opening said ports.

4. In an apparatus of the character described, the combination of a tank, a shaft inside of said tank carrying an agitator fixed, and a fan loose thereon, and means outside of said tank whereby said fan may be thrown into engagement with said agitator.

In testimony whereof I hereunto affix my signature in the presence of two witnesses.

EDWIN J. NELSON.

Witnesses:

HELEN M. McLOUGHLIN,
ELEANOR T. DE GIORGI.
